CLAIM

The ornamental design for a computer, as shown and described.

DESCRIPTION

FIG. 1 is a top front and right side perspective view of a computer according to the present invention and illustrated with its display in a closed position;

FIG. 2 is a top plan view thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a bottom plan view thereof;

FIG. 8 is a top front and right side perspective view of a computer of FIG. 1 with the display in an open intermediate position;

FIGS. 9 and 10 are right and left side elevational views, respectively, of the computer of FIG. 8, with the display in a full open position; and,

FIG. 11 is a top plan view of the computer with the display in the full open position, as illustrated in FIGS. 9 and 10.
